UNITED STATES PATENT OFFICE

CHRIST PAPOUCHIS, OF FAR ROCKAWAY, NEW YORK

GAME APPARATUS

Application filed August 25, 1928. Serial No. 302,114.

The present invention relates to game apparatus in which the player directs balls at suitable targets, the relative importance of which may vary in accordance with a predetermined plan. When one of the targets is struck by a ball, it registers, upon a suitable recording mechanism, the number of points given to such target and, as additional balls are directed at the targets, the score is accumulated to give a total after any desired number have been played. A game of this character is shown and described in the patent to Christ Papouchis, No. 1,461,432, dated July 10, 1923, and the present invention embodies certain improved features which render the apparatus entirely automatic and capable of being operated by a coin receiving mechanism. In this manner, the number of attendants required for a given number of game devices is greatly reduced and each game is completely controlled by the player who inserts coins from time to time in accordance with a predetermined setting or design of the apparatus.

More particularly, the invention embodies a given apparatus in which the scoring mechanism and ball releasing device is entirely controlled by a coin receiving apparatus which automatically renders the game device capable of recording.

An object of the invention is to provide a game apparatus controlled as above mentioned, the apparatus being designed to control, accurately and positively, the playing of the game, whereby a definite number of balls may be directed at the targets upon the insertion of a coin of the required denomination in the coin receiving apparatus. The simplicity of the mechanism not only insures accurate and positive operation, but also requires but little attention from time to time to maintain it in operative condition.

Other objects will appear as the invention is described more fully in connection with the accompanying drawings wherein:

Figure 1 is a view in section, taken on line 1—1 of Figure 2, and looking in the direction of the arrows.

Figure 2 is a plan view of the game apparatus shown in Figure 1.

Figure 3 is a view in section, taken on line 3—3 of Figure 1, and looking in the direction of the arrows.

Figure 4 is a view in section, taken on line 4—4 of Figure 1, and looking in the direction 55 of the arrows.

Figure 5 is a view in section, taken on line 5—5 of Figure 1, and looking in the direction of the arrows.

Figure 6 is an enlarged view in section, 60 taken on line 6—6 of Figure 9, and looking in the direction of the arrows.

Figure 7 is a view in section, taken on line 7—7 of Figure 9, and looking in the direction 65 of the arrows.

Figure 8 is a view in section, taken on line 8—8 of Figure 9, and looking in the direction of the arrows.

Figure 9 is a view in section, considerably enlarged and taken on line 9—9 of Figure 1, 70 looking in the direction of the arrows.

Figure 10 is a detail view in section, taken on line 10—10 of Figure 6.

Referring to the above drawings, *a* indicates a ball alley or other suitable surface 75 upon which balls are to be rolled toward targets *b*. These targets are independently pivoted on shaft *b'* and, when struck by a ball, swing rearwardly to permit the ball to pass below the shaft and into trough *b''* 80 to be returned to a trough *b'''* which extends along the side of the alley. Vanes *b'* may be provided in front of the targets to direct the balls in the proper channels in order that a ball may not strike more than one 85 target at a time. In the present instance, the two outside targets have been given the value of ten points each, the middle target the value of thirty points, and the two intermediate targets the value of twenty points 90 each. Each target is provided with an upwardly extending arm *b'* which is pivotally connected to suitable levers for causing the score registering mechanism to function as described presently.

A cylindrical carrier *c* is rotatably mounted upon shaft *c'* and provided with a ratchet and pawl mechanism *c''* to prevent its rotation in a reverse direction. Upon this cylindrical carriage are pivoted display numbers 100

*c*³ for indicating the score at any given time. As the carriage is rotated, the display numbers fall against pin *c*⁴, continued rotation causing the score cards to be released and 5 swung into a display position. The entire scoring mechanism is housed in a container *d* provided with an aperture *d*' through which the score cards are displayed. Mounted upon the shaft *c*' is a yoke member *e* which carries a pawl *e*' to engage the ratchet wheel 10 *c*². The yoke member is provided with a suitable weight *e*² which normally exerts a force upon the ratchet wheel *c*² to cause the carriage to be rotated.

15 Movement of the yoke *e* is prevented by a series of hooked levers *f*', *f*² and *f*³, which are mounted upon a shaft *f*. Lever *f*' is connected, through a U-shaped extension *f*⁴ and links *f*⁵, with the arms *b*⁵ of the two outer targets. Lever *f*², provided with a similar U-shaped extension *f*⁶, is connected with the arms *b*⁵ of the intermediate targets, and the hook shaped lever *f*³ is connected to the middle target through U-shaped extension *f*⁷ and a link *f*⁸. When a target is struck, it moves to the right in Figure 6 and causes the appropriate hook shaped lever or levers *f*', *f*² and *f*³ to be moved out of the path of the yoke *e*. Either end target *b* will cause only the lever *f*' to be moved to the right, as seen in Figure 6, and permit the yoke *e* to be turned under influence of the weight *e*² until it is in engagement with the hook shaped lever *f*². This movement corresponds to a movement of the cylindrical carriage sufficient to cause one score card to ride off of pin *c*⁴ and fall into display position behind the aperture *d*'. Either intermediate target *b*', when struck by a ball, will move the U-shaped extremity *f*⁶ of lever *f*² in such manner that the U-shaped extremity *f*⁴ will be carried with it to rock both hooked levers *f*' and *f*² to the right as seen in Figure 6 and thus permit the yoke *e* to be moved into engagement with the lever *f*³. This movement corresponds to a movement of the cylindrical carriage sufficient to permit two score cards to pass over the pin *c*⁴ and register a greater score, in the present instance twenty points. In like manner, the middle target *b* carries all of the U-shaped extensions *f*⁴, *f*⁶ and *f*⁷ with it to disengage all of the hooked levers and to permit the yoke *e* to be moved an equivalent of three steps, thus displaying the highest score possible to be made with one ball.

As the ball strikes a target and registers the proper score as described above, it rolls over a platform *g* which is pivoted to the alley at *g*'. This platform is counterbalanced by a weight *g*² in such manner that when a ball rolls over the platform, the weight is lifted and the platform drops, carrying with it link *g*³ and lever *g*⁴ which is pivoted upon shaft *c*'. The lever *g*⁴ is formed

with a pin *g*⁵ which engages the yoke member *e* to return it into engagement with the hook shaped lever *f*'. By means of this construction, the scoring mechanism is reset after each ball has been rolled, to enable the proper score to be registered when a subsequent ball strikes one of the targets. After depressing platform *g* the ball rolls into trough *b*² and down trough *b*³ ready to be played again.

When a predetermined number of balls have been played, it is necessary to reset the entire scoring mechanism to the zero position, the condition in which a player begins the game. In order to accomplish this automatically, a motor *h* is mounted in a suitable position to drive a worm wheel *h*' and spur gear *h*² through worm *h*³ and spur pinion *h*⁴, respectively. Gear *h*² is mounted upon a shaft *h*⁵ which is carried by a bracket *h*⁶ within the housing *d*. Mounted upon the shaft *h*⁵ is a sleeve *h*⁷, formed with an arm *h*⁸, having a lateral extension *h*⁹. Pivoted upon the lateral extension is a dog *h*¹⁰ having a depending lip *h*¹¹ and a lateral extension *h*¹². A spring *h*¹³ may be provided to maintain the dog yieldingly against the lateral extension *h*⁹.

Gear wheel *h*² is provided with an arm *h*¹⁴ upon the end of which is mounted a roller *h*¹⁵. The path of roller *h*¹⁵ coincides with the arc of movement of the depending lip *h*¹¹ upon the pivoted dog *h*¹⁰. When the gear *h*² is rotated by the motor, the roller *h*¹⁵ engages the depending lip of the dog and moves lever *h*⁸.

A lever *i* is mounted to rotate with sleeve *h*⁷ and transmit its movement through links *i*', *i*², spring *i*³ and pull cord *i*⁴ to a drum *c*⁵ which is mounted on shaft *c*'. This drum has secured thereto a yoke *c*⁶ which carries a dog *c*⁷, the latter engaging a lug *c*⁸ upon the cylindrical carriage to transmit the movement of the drum to the latter. The dimensions of the drum *c*⁵ and the lever *i* may be such that a predetermined movement of the gear wheel *h*² will move the cylindrical carriage a complete revolution, thus resetting the scoring mechanism to zero from any position to which it has been moved. In the construction shown, approximately half a turn of the gear wheel is sufficient to move the cylindrical carriage to this extent and, accordingly, a pin *j* is positioned in the path of the lateral extension *h*¹² of the dog *h*¹⁰ so that a predetermined movement of the gear wheel *h*² and lever *h*⁸ will cause the lateral extension *h*¹² to engage the pin *j*. Continued movement of the lever *h*⁸ will result in rocking the dog laterally, as indicated in dot and dash lines in Figure 10, to permit the roller *h*¹⁵ to be disengaged and the arm *h*⁸ to be returned to its normal position. Figures 6, 9, and 10 illustrate this operation and show the manner in which

the scoring mechanism is returned to the zero position.

Simultaneously with the resetting of the scoring mechanism a ball metering mechanism is operated to release a predetermined number of balls for playing. This mechanism is somewhat similar to that shown in the above mentioned patent and comprises a weight operated detent k mounted upon 5 a yoke shaped member k' which is pivoted to the trough b^3 at k^2 . The detent extends through the bottom of the trough and is formed with a platform k^3 over which the balls roll, preventing the detent from returning to its normal position until a predetermined number of balls have been released. An arm k^4 is connected through a link k^5 with a crank arm k^6 upon a suitable 10 shaft k^7 , cranks k^8 and k^9 also being mounted to turn with the crank arm k^6 . Spring k^{10} normally holds the cranks in the position shown in Figure 1 and prevents the balls from being released. A gate l is pivoted upon the trough b^3 at l' and operated from 15 crank k^8 through cord l^2 . When the detent k is moved to release the balls, gate l drops to permit only the balls between the gate and detent to be released, all remaining balls being held by the gate until the releasing 20 mechanism has been returned to the position shown in Figure 1.

In order that this ball releasing, or metering mechanism may be operated simultaneously with the resetting of the scoring mechanism, a connecting link k^{11} is mounted 25 between lever k^9 and lever i . When the gear wheel h^2 rotates to reset the scoring mechanism, lever k^9 is moved to the right, as seen in Figure 1, and a predetermined number of 30 balls is released.

The coin receiving mechanism may consist of a slot m at the bottom of which an electric contact m' is mounted. A contact m^2 is pivotally mounted and normally maintained in the position shown in Figure 1 by 35 a spring m^3 .

When the coin is deposited in the slot it closes the contact between m' and m^2 to complete the circuit, including the motor h , through wires m^4 . As the gear h^2 continues its movement after the roller h^{15} has been released from engagement with the pivoted dog h^{10} , the link k^{11} moves to the left in Figure 1. During this movement, it is desirable 40 that the coin be released and the motor circuit broken. Accordingly, a link n is connected to a crank n' pivoted at n^2 and normally maintained in the position shown in Figure 1 by means of a spring n^3 . The crank is provided 45 with an arm n^4 , at the end of which is a pivoted dog n^5 which engages a rearwardly extending arm m^5 on the contact m^2 . During the movement of the gear wheel h^2 to reset the scoring mechanism, the pivoted dog n^5 passes over the arm m^5 without affecting the electrical circuit.

As the links k^{11} and n move toward the left in Figure 1, the dog n^5 moves upwardly to engage the extension m^5 thus operating contacts m' , m^2 to release the coin and break the circuit.

From the foregoing description it will be seen that the game is entirely automatic in operation, the player controlling such operation by depositing coins in the coin receiving mechanism m . It is further apparent that the number of balls released is always the same since the ball releasing mechanism is controlled automatically, the player having no opportunity for manipulating such mechanism. The scoring mechanism is operated in successive stages by the movement of the ball and the device is infallible in operation.

While the invention has been described in connection with the specific construction shown in the accompanying drawings, it is not to be limited, save as defined in the appended claims.

I claim as my invention:

1. In a game apparatus, the combination of a scoring mechanism, a ball actuated device, means to operate the scoring mechanism from the ball actuated device, and ball actuated means for resetting the operating mechanism.

2. In a game apparatus, the combination of a scoring mechanism, a ball actuated device, means to operate the scoring mechanism from the ball actuated device, and means actuated by the ball, after actuating the first device, for resetting the operating mechanism after it has caused the scoring mechanism to register.

3. In a game apparatus, the combination of a scoring mechanism, a ball actuated device, weight actuated means for operating the scoring mechanism, means operated by the ball actuated device to release the weight actuated means, and ball actuated means for resetting the weight actuated means.

4. In a game apparatus, the combination of a rotatable scoring mechanism, means to permit rotation thereof in one direction only, a ball actuated device, weight actuated means for rotating the scoring mechanism, means actuated by the ball actuated mechanism for permitting the weight actuated means to operate, and ball actuated means for resetting the weight actuated means.

5. In a game apparatus, the combination of a rotatable scoring mechanism, means to permit rotation thereof in one direction only, a ball actuated device, means for rotating the scoring mechanism, means normally acting on the rotating means to cause it to operate, means normally engaging the rotating means to prevent its operation, means operated by the ball actuated means to release the engaging means, and ball actuated means for returning the rotating means to its initial

engaged position after it has rotated the scoring mechanism.

6. In a game apparatus, the combination of a rotatable scoring mechanism, means to permit rotation thereof in one direction only, a plurality of ball actuated devices, means normally tending to rotate the scoring mechanism means normally engaging the score rotating means to prevent movement thereof, means actuated by all of the ball actuated devices for releasing the engaging means, an additional engaging means in the path of movement of the score rotating means, means actuated by certain of the ball actuated devices for releasing the second engaging means, and ball actuated means for returning the rotating means to its position in engagement with the first engaging means.

7. In a game apparatus the combination of a rotatable scoring mechanism, means to permit rotation thereof in one direction only, a plurality of ball actuated devices, means normally tending to rotate the scoring mechanism means normally engaging the score rotating means to prevent movement thereof, means actuated by all of the ball actuated devices for releasing the engaging means, a plurality of additional engaging means spaced in the path of movement of the score rotating means to limit, selectively, the movement thereof, means actuated by certain of the ball actuated devices for releasing predetermined of the engaging means, and ball actuated means for returning the rotating means to its position in engagement with the first engaging means.

8. In a game apparatus, the combination of a scoring mechanism, a ball actuated device, means to operate the scoring mechanism from the ball actuated device, ball actuated means for resetting the operating mechanism, and power means for returning the scoring mechanism to zero.

9. In a game apparatus, the combination of a scoring mechanism, a ball actuated device, means to operate the scoring mechanism from the ball actuated device, ball actuated means for resetting the operating mechanism, a motor, means operated by the motor to return the scoring mechanism to zero, and means for controlling the motor.

10. In a game apparatus, the combination of a scoring mechanism, a ball actuated device, means to operate the scoring mechanism from the ball actuated device, ball actuated means for resetting the scoring mechanism, a motor, an arm connected to the scoring mechanism to reset the same to zero, means operated by the motor to engage the arm, and means to disengage the motor operated means after the arm has effected the resetting of the scoring mechanism.

11. In a game apparatus, the combination of a scoring mechanism, a ball actuated device, means to operate the scoring mech-

anism from the ball actuated device, ball actuated means for resetting the scoring mechanism, a motor, an arm connected to the scoring mechanism to reset the same to zero, a second arm driven by the motor, a latch on the first arm to engage the second arm, and means to disengage the latch after the resetting operation has been effected.

12. In a game apparatus, the combination of a scoring mechanism, a ball actuated device, means to operate the scoring mechanism from the ball actuated device, ball actuated means for resetting the scoring mechanism, a motor, an arm connected to the scoring mechanism to reset the same to zero, a second arm driven by the motor, a latch pivoted on the first arm to engage the second arm, and a pin to engage the latch to release the first arm after a predetermined movement thereof to reset the scoring mechanism.

13. In a game apparatus, the combination of a scoring mechanism, a ball actuated device, means to operate the scoring mechanism from the ball actuated device, ball actuated means for resetting the scoring mechanism, a motor, means to control the motor, an arm connected to the scoring mechanism to reset the same to zero, a second arm driven by the motor, a latch pivoted to the first arm to engage the second arm, means operated from the second arm to reset the motor controlling means, and a pin to engage the latch to release the first arm after a predetermined movement thereof to reset the scoring mechanism.

14. In a game apparatus, the combination of a scoring mechanism, a ball actuated device, means to operate the scoring mechanism from the ball actuated device, power means for resetting the scoring mechanism, a ball container, means actuated by the power means for releasing a predetermined number of balls for play and means on the last named means for holding the same in releasing position by the balls released.

15. In a game apparatus, the combination of a scoring mechanism, a ball actuated device, means to operate the scoring mechanism from the ball actuating device, power means for resetting the scoring mechanism, a ball container, means actuated by the power means for releasing a predetermined number of balls for play, and ball actuated means for holding the last named means in releasing position.

This specification signed this 23rd day of August A. D. 1928.

CHRIST PAPOUCHIS.
